FASTENING FOR BUSINESS MACHINES

Edwin C. Wick, Upper Darby, Pa.

Application May 4, 1944, Serial No. 534,013

2 Claims. (Cl. 248—22)

This invention relates to fastenings for business machines such as typewriters, adding machines and the like.

Numerous fastening devices have heretofore been proposed for business machines but none of these have proven wholly satisfactory. The fastenings heretofore available, in many instances, contributed to the transmission of noise, or were lacking in strength or were lacking in adaptability to the various machines and desks available, or were unsuited for shifting of the machine to other locations, or had other objectionable features.

In accordance with the present invention a fastening for business machines is provided which reduces the noise transmitted from the machine, prevents sounding board effects of the desk, table or other support, while at the same time is simple and rugged in construction.

In accordance with the present invention also a fastening for business machines is provided which is particularly adapted for the movement or shifting of the machine from one location to another as desired while at the same time providing adequate support and clamping of the machine at each location.

The nature and characteristic features of the invention will be more readily understood from the following description, taken in connection with the accompanying drawing forming part hereof, in which:

Figure 1 is a vertical sectional view taken approximately on the line 1—1 of Fig. 2 and showing the manner of connecting the fastening and a business machine;

Fig. 2 is a plan view of the fastening with the machine removed;

Fig. 3 is a view similar to Fig. 2 showing the manner in which one portion of the fastening is slidable with respect to the other for shifting the machine to another location;

Fig. 4 is a vertical sectional view taken approximately on the line 4—4 of Fig. 2; and

Fig. 5 is an enlarged fragmentary vertical sectional view taken approximately on the line 5—5 of Fig. 2.

It should of course be understood that the description and drawing herein are illustrative merely, and that various modifications and changes may be made in the structure disclosed without departing from the spirit of the invention.

Referring more particularly to the drawing a support is illustrated generally at 10, upon which a business machine, such as a typewriter, adding

machine, or the like, having a frame portion 11, is adapted to be secured. The support 10 may be a table, or may be the typewriter supporting portion of a typewriter desk of the type which is adapted to be tilted to an inclined portion or of the type which is adapted to be swung to a vertical position for storage of the typewriter or the like when the same is not in use. The support 10 may be of wood, metal or the like.

The fastening proper is preferably made in two sections, one of which, is a central section 12 and is adapted to be permanently mounted or secured rigidly in position on the support 10 by means of screws 13 or the like, which extend into the support 10. The screws 13 may be surrounded by spacer washers 13' of rubber or the like.

The central section 12 preferably consists of an upper flat plate portion 14, preferably of sheet metal, with parallel side walls or edges 15 inturned

20 at an acute angle. A pad 16, preferably of hair felt, rubber or similar resilient shock absorbing and sound deadening material, is provided of a thickness such as to space the lower extremities of the edges 15 from the support 10. The pad 16 is preferably secured to the underface of the plate portion 14 by means of a suitable adhesive. The central section 12 also has a front edge portion 17 which is angularly inturned.

The fastening also includes an outer section 18 30 upon which the frame 11 of the machine is mounted and secured in position in any suitable manner, such as by screws 19 extending upwardly through openings 20 and into bosses 21 in the frame 11.

35 The outer section 18 preferably consists of an upper flat plate portion 22, preferably of sheet metal with outer parallel downwardly extending side edges 23 and a downwardly extending front edge 24. The plate portion 22 is preferably provided with parallel inner walls or edge portions 25 angularly disposed with respect to the upper surface of the plate portion 22 and complementary to the side edges 15 of the central section 12 for sliding engagement along the lower faces of the edges 15.

The outer section 18 preferably also includes an angularly disposed edge portion 26 for contact with and engagement by the front edge portion 17 of the central section 12. The outer section 18 preferably includes a pad 27, of hair felt, rubber or similar resilient shock absorbing and sound deadening material, and of a thickness to space the edge portions 23, 24, 25 and 26 from the support 10, and resiliently support these edge portions.

The machine when secured to the outer section 18 may be readily slid therewith to position with the edges 25 of the outer section 18 in frictional engagement beneath the edges 15 and with the edge portion 26 of the outer section 18 in contact with the edge portion 17 of the central section 12. The machine will then be solidly supported. The pad 27 effectually deadens any sound which might tend to be transmitted to the central section 12 and the pad 16 is of further assistance for the same purpose. The pads 27 and 16 also prevent noise in the sections 18 and 12. The pads 16 and 27 also reduce or eliminate any sounding board effect of the support 10. At the same time the fastening is of adequate strength to support the machine whether the support 10 is tilted or is moved to a vertical position. If desired also the machine may be readily removed with the outer section 18 secured thereto, by sliding the outer section 18 along the support 10 until the edge portions 25 are free from engagement with the edges 15. The machine and the outer section 18 may then quickly be mounted upon another central section 12 at some other location where it is desired to use the same.

I claim:

1. A fastening for business machines comprising a central section adapted to be secured to a support and an outer section adapted to have a business machine secured thereto, and complementary side walls on said sections for sliding interlocking engagement, each of said sections having a pad of resilient sound absorbing material disposed thereunder for spacing said section and said walls from the support, said pads urging the side walls of the respective sections into engagement.
2. A fastening for business machines comprising a central section consisting of a flat member of sheet material adapted to be rigidly secured to a support and having outer side walls inclined at acute angles with respect to said flat member, an outer section consisting of a second flat member of sheet material and having complementary inclined walls for engagement with said outer side walls, and each of said sections having a pad of resilient sound absorbing material extending thereunder and in engagement with the under side of said flat member for spacing said section from the support, said pads urging the side walls of the respective flat members into engagement.

EDWIN C. WICK.
